UNITED STATES PATENT OFFICE.

ANDREW L. WILLIAMS, OF CHICAGO, ILLINOIS.

DESIGN FOR A BADGE.

No. 39,393.

Specification for Design.

Patented July 7, 1908.

Application filed May 2, 1908. Serial No. 430,618. Term of patent 7 years.

To all whom it may concern:

Be it known that I, ANDREW L. WILLIAMS, a citizen of the United States of America, and a resident of Chicago, in the county of Cook and State of Illinois, have invented a new, original, and ornamental Design for Badges, of which the following is a specification, reference being had to the accompanying drawing, forming part thereof.

The figure shows a face view of a badge, showing my new design.

I claim:

The ornamental design for a badge, as shown.

ANDREW L. WILLIAMS.

Witnesses:

CLARENCE J. WILLIAMS,
MARY M. DILLMAN.
